UNITED STATES PATENT OFFICE.

CARL D. BROWN, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Original application filed May 22, 1922, Serial No. 562,581. Divided and this application filed August 30, 1923. Serial No. 660,130.

To all whom it may concern:

Be it known that I, CARL D. BROWN, a citizen of the United States, and a resident of Hopedale, in the county of Worcester and State of Massachusetts, have invented an Improvement in Feeler Mechanisms for Looms, of which the following description, in connection with the accompanying drawings, is a specification, like characters on the drawings representing like parts.

This invention relates to feeler mechanisms for filling replenishing looms whereby the filling is replenished from time to time.

Feeler mechanisms of the so called "side swipe" type initiate replenishment of filling when the feeler is moved longitudinally along the filling carrier, and to restrain the feeler from such movement it is now the usual practice to provide a feeler tip which has teeth or projections to sink into the filling when a working supply is present. To insure the proper holding effect of the teeth or projections of the feeler by the filling on a detecting beat, the feeler has ordinarily been provided with a yielding device such as a spring for holding the feeler in its rearward feeling position, and where the feeler enters the shuttle at right angles to the lay movement it is now the usual practice to provide a second spring for effecting movement of the feeler longitudinally of the shuttle when the filling is substantially exhausted.

One of the objects of the present invention is to provide a feeler mechanism in which the feeler is under the control of a single spring which not only serves to cause the teeth or projections of the feeler tip to sink into the filling on a detecting beat when a working supply is present, but also acts to move the feeler in a direction longitudinally of the shuttle when the filling is substantially exhausted.

In accordance with the present invention, the spring which acts upon the feeler to perform the stated functions has a bend between its ends, so that as the feeler is moved forwardly on a detecting beat by the forward pressure of a surface within the shuttle, the lateral bend in the spring is increased, thereby imparting a tendency to the feeler to move longitudinally of the

shuttle. A construction such as described enables the feeler to contact with the filling on a detecting beat with a very delicate pressure without causing injury to the filling, and as the feeler is moved forwardly the spring acts with increasing tendency to impart movement of the feeler longitudinally of the shuttle.

The various novel features of the invention and new combination of parts will best be understood from the following description and the accompanying drawings of one good practical form thereof.

In the drawings:

Fig. 1 is a plan view of the feeler mechanism containing the present invention, with the top plate of the feeler stand removed, and showing parts of the shuttle-box and shuttle in section;

Fig. 2 is a plan view with the top plate of the feeler stand in place and showing the relation of parts when the filling is substantially exhausted on a detecting beat and the feeler is moved in a direction longitudinally of the shuttle; and

Fig. 3 is a vertical section through the feeler stand and feeler.

It has not been deemed necessary to illustrate the replenishing mechanism, nor many of the loom parts, because the details of such mechanism and parts form no feature of the present invention, which more directly concerns the means for controlling the feeler.

The shuttle-box and shuttle may be of usual construction, the latter being provided with bobbin holding jaws, as usual, for holding the filling carrier or bobbin.

As shown, the shuttle-box 1 is provided with an opening 2 in its front wall, and the shuttle 3 is similarly provided with an opening 4 which registers with the opening in the front wall of the shuttle-box for the entrance of the feeler into the shuttle on a detecting beat to feel for the filling.

The shuttle is shown as provided with the usual bobbin holding jaws 5 which support the filling carrier 6, and while the invention to be described is well adapted for this character of shuttle construction wherein the filling carrier itself is ejected and a new supply furnished the shuttle when that in the running shuttle is substantially exhausted, it will of course be understood that

it may be advantageously applied also to the other well-known type of filling replenishing loom wherein the shuttle itself is changed.

5 The feeler stand 7 is supported at the front of the loom, preferably on the usual bracket extending from the shipper stand, and since these features of the construction are now well known, the details thereof are 10 not herein shown and described. The feeler stand shown consists of the bottom plate 8 and the top plate 9 which may be appropriately secured together by screws 10 which pass through an opening 11 in the 15 side extending flanges of the top and bottom plates and such screws 10 may if desired be employed for securing the feeler stand as a whole to the loom frame.

Between the bottom and top plates 9 and 20 8 of the feeler stand a guide recess 12 is provided which, as hereinafter described, furnishes ample space for the lateral bending or buckling of the spring which acts upon the feeler. If desired, also, the top 25 plate may be further secured to the bottom plate by additional screws 13 passing through or into the overlying flange portions of the top and bottom plates.

The rearward portion of the feeler stand 30 is provided with a laterally extending guideway 14 in which is mounted the slide 15 having an opening 16 through which the feeler 17 extends, and the slide 15 has connected thereto a transmitter 18, the construction being such that should the slide 35 15 be moved laterally to the right, as shown in the present instance, the transmitter 18 will position parts of the filling replenishing mechanism for effecting replenishment 40 of filling.

The slide 15 is confined in its guideway 14 between the top and bottom plates of the feeler stand, substantially as indicated in Fig. 3, and rearward of the slide 15 the 45 feeler stand is provided with an enlarged opening 19 to permit the feeler 17 to move in a direction longitudinally of the shuttle, as indicated in Fig. 2.

The feeler 17 is provided with a filling 50 engaging tip 20 which in the present instance of the invention is shown as of the character described in the Carl D. Brown application, Serial No. 562,581, filed May 22, 1922, of which the present application 55 is a division. So far, however, as the essentials of the present invention are concerned, the feeler tip may be of any usual character which by engagement with a working supply of filling on a detecting beat will restrain the feeler from movement longitudinally of the shuttle until the filling is substantially exhausted, and in order to lighten the feeler and impart delicacy of action, it 60 may be provided with a slot 21.

65 The feeler 17 is under the control of a

single spring, as shown, which normally acts to hold the feeler in its rearward feeling position and, on a detecting beat, imparts to the feeler a tendency to move longitudinally of the shuttle. In carrying this feature of the invention into effect the spring 70 22 has one end 23 secured to the feeler and its other end is secured to a point forward 75 of the feeler and preferably in a swivel block 24 mounted for rocking movement between the top and bottom plates of the feeler stand, as indicated in Fig. 3.

The spring 22 shown is of the coiled type, but any other form of spring may be advantageously employed which will act to hold the feeler in its rearward feeling position and be susceptible of bending or buckling when the feeler is moved forwardly by the surface within the shuttle on a detecting beat.

80 Between the two ends of the spring, the latter is bent to form an initial bend or buckling point in the spring and, as shown, this is accomplished in the present instance by a deflector 25 which may be conveniently 85 formed as a lateral projection secured to or as part of the feeler stand, the construction being such that when the feeler is in its rearward feeling position, as indicated by the dotted lines, Fig. 1, the spring 22 will have 90 formed therein substantially at the point 26 an initial bend, so that should the feeler meet a working supply of filling in the shuttle on a detecting beat, as indicated by 95 full lines, Fig. 1, the spring 22 will buckle 100 or bend laterally in the guiding space 12 between the upper and lower plates of the feeler stand, thereby imparting to the feeler a tendency to move longitudinally of the 105 shuttle about the point 27 of the feeler stand as a fulcrum.

As hereinbefore stated, one end of the spring is secured at 23 to the feeler and its other end is secured to the swivel block 24. The result is that when the feeler is moved 110 into its rearward feeling position by a straightening tendency of the spring 22, its rearward movement will be limited by the permissive straightening effect of the spring 22 as it assumes the dotted line position in 115 Fig. 1. If desired, however, a stop 28 may be provided on the feeler to engage the slide 15 or some other portion of the mechanism to limit the rearward movement of the feeler under the straightening action of the spring 120 22.

125 From the construction described as one good practical form of the present invention, it will be noted that the feeler 17 is under the control of a single spring 22, and that when the feeler is in its rearward feeling position the spring 22 will have imparted thereto a bend intermediate its ends, the result being that when the feeler moves 130 forwardly the spring 22 will further bend

or buckle, as indicated by full lines, Fig. 1, and impart to the feeler a tendency to move in a direction longitudinally of the shuttle. To effect the initial bend in the spring 22 5 the deflector may be variously contrived to bear upon the spring between its ends, and the deflecting action of the spring may be changed from one side to the other, in order that the feeler may act either in the direction 10 towards the tip of the bobbin or towards the base or head.

Likewise the end of the spring 22 may be secured to the feeler in any appropriate manner, but as shown in the present instance, 15 the feeler is provided with a socket into which the end of the spring 22 is inserted and held, and likewise the other end of the spring may be secured to the swivel block 24 by a recess formed in the block into which 20 the end of the spring is inserted.

From the construction described it will be apparent that the spring 22 normally acts upon the feeler to hold it in its rearward feeling position, and is provided with a bend 25 between the ends of the spring whereby when the feeler is moved forwardly on a detecting beat, the spring being free between its ends will further buckle or bend and impart to the feeler a tendency to move in a direction longitudinally of the shuttle and effect such movement as indicated in Fig. 2 when the filling is substantially exhausted.

What is claimed is:

1. In a feeler mechanism for looms, the 35 combination of a feeler mounted for movement towards and from the front of the loom and also in a direction longitudinally of the shuttle, a spring having one end secured to the feeler and the other end secured 40 to the feeler stand normally acting to impel the feeler rearwardly and itself limiting the rearward movement of the feeler, and a deflector to engage the spring between its ends and cause the spring to buckle as the feeler 45 is moved forwardly on a detecting beat to impart a tendency for feeler movement longitudinally of the shuttle.

2. In a feeler mechanism for looms, the 50 combination of a feeler mounted for movement in a direction longitudinally of the shuttle and held from such movement by engagement with the filling until substantial exhaustion thereof, a spring having one end connected to the feeler and the other end 55 to the feeler stand and normally tending to straighten between its ends, and a deflector which acts upon the spring between its ends to cause the spring to buckle and impart a tendency to feeler movement longitudinally of the shuttle when the feeler 60 is moved forwardly on a detecting beat,

3. In a feeler mechanism for looms, the 65 combination of a feeler that enters the shuttle in a direction at right angles to the lay movement and movable in a direction longi-

tudinally of the shuttle to call for replenishment of filling, a spring secured at one end to the feeler and at its other end to the feeler stand, and normally acting to impel the feeler rearwardly into feeling position, 70 and a deflector which causes a lateral bend in the spring between its end when the feeler is in rearward feeling position and limits its tendency to straighten.

4. In a feeler mechanism for looms, the 75 combination of a feeler mounted for movement longitudinally of the shuttle and held from such movement by engagement with the filling until substantial exhaustion thereof, a coiled spring having one end secured 80 to the feeler and its other end to the feeler stand and normally acting to maintain the feeler in its rearward feeling position, and a deflector which is engaged by a part of the spring between its ends to form a bend in 85 the spring when the feeler is in rearward feeling position that the spring may tend to move the feeler longitudinally of the shuttle as the feeler moves forwardly on a detecting beat.

5. In a feeler mechanism for looms, the 90 combination of a feeler stand, a feeler mounted for movement in a direction longitudinally of the shuttle and held from such movement by the filling on a detecting beat 95 until substantial exhaustion of filling, a rocking bearing at the front of the feeler stand, a spring connected at one end to the feeler and at its other end to the rocking bearing and normally tending to straighten itself to move the feeler to rearward feeling position, and a deflector which engages the spring between its ends and prevents straightening of the spring that the spring may be further deflected as the feeler moves forwardly and tends to move the feeler longitudinally of the shuttle.

6. In a feeler mechanism for looms, the 100 combination of a feeler mounted for movement longitudinally of the shuttle and held from such movement by engagement with the filling until substantial exhaustion thereof, a spring mounted with one end secured to the feeler and the other end secured at a point forward of the feeler that it may 105 bend or buckle between its ends, and a deflector which bears upon the spring between its ends when the feeler is in rearward feeling position and prevents the spring from straightening.

7. In a feeler mechanism for looms, the 110 combination of a feeler stand, a feeler mounted for movement longitudinally of the shuttle, a spring having one end secured to the feeler and the other end secured at a point forward of the feeler and normally tending to straighten between these points, 115 said spring having a lateral bend between its ends that the part of the spring between its ends may bend or buckle further when 120

the feeler is moved frontwardly by a surface within the shuttle on a detecting beat and impart a tendency in the feeler to move in a direction longitudinally of the shuttle.

5 8. In a feeler mechanism for looms, the combination of a feeler stand, a feeler mounted for movement longitudinally of the shuttle, a coiled spring normally tending to straighten having one end secured to the
10 feeler and the other end secured at a point frontward of the feeler and by such straightening tendency causing movement of the feeler to rearward feeler position, said

spring having a lateral bend between its ends that the point of the spring between 15 its ends may bend or buckle further when the feeler is moved frontwardly by a surface within the shuttle on a detecting beat and impart a tendency in the feeler to move in a direction longitudinally of the shuttle, 20 and means actuated by such movement of the feeler on a detecting beat to effect replenishment of filling.

In testimony whereof, I have signed my name to this specification.

CARL D. BROWN.
